UNITED STATES PATENT OFFICE.

FRIEDRICH E. BRUECKNER, OF LAWRENCE, MASSACHUSETTS.

BEER-FAUCET.

No. 919,124.

Specification of Letters Patent. Patented April 20, 1909.

Application filed March 9, 1908. Serial No. 420,018.

To all whom it may concern:

Be it known that I, FRIEDRICH E. BRUECKNER, a citizen of the United States, residing at Lawrence, in the county of Essex and 5 State of Massachusetts, have invented certain new and useful Improvements in Beer-Faucets; and I do declare the following to be a full, clear, and exact description of the invention, such as will enable others skilled in 10 the art to which it appertains to make and use the same.

This invention relates to improvements in beer faucets.

The object of the invention is to provide a 15 faucet of this character having means whereby the valve is opened and closed by a removable key which also serves as a discharge spout.

With this and other objects in view, the 20 invention consists of certain novel features of construction, combination and arrangement of parts as will be described and particularly pointed out in the appended claims.

In the accompanying drawings, Figure 1 is 25 a sectional view through a portion of a barrel showing the faucet applied thereto, parts of the latter being broken away and in section, and showing the valve of the faucet in a closed position; Fig. 2 is a side view of the 30 valve, with parts broken away and in section and showing the valve in an open position; Fig. 3 is a longitudinal sectional view of the faucet showing the key applied thereto; Fig. 4 is an inner end view of the faucet showing 35 the position of the closing cams when the valve is open; Fig. 5 is an end view of the valve seat showing one of the opening cams and inlet ports; Fig. 6 is an inner side view of the valve showing the opposing set of opening 40 cams, and the guide fingers on said valve; and Fig. 7 is an edge view of the valve and a portion of the closing mechanism.

Referring more particularly to the drawings, 1 denotes the cylindrical body portion 45 of the faucet, having on its outer side a series of coarse wood threads, 2, by means of which the same is secured in the side of the barrel or cask to which it is applied. On the inner end of the body portion 1 is formed a valve seat, 3, in which is arranged at diametrically opposite points discharge passages 4. In the body portion, substantially midway between its ends, is arranged an inwardly projecting annular flange, 5, which forms a seat to receive

the inner end of an operating key, herein- 55 after described. In the inner wall of the body portion, adjacent to its outer open end, are formed oppositely disposed cam locking recesses, 6, adapted to receive the locking lugs of said key. 60

Revolvally mounted in a centrally disposed aperture formed in the valve seat, 3, is a valve operating stem, 7, having on its outer end an annular enlargement, 8, adapted to bear against the inner side of the valve 65 seat, 3, and with a squared head, 9, to receive the inner end of the operating key before mentioned. The inner end of the stem, 7, is squared and on said squared portion is slidably mounted a valve, 10, said valve having 70 formed on its inner side, and preferably at diametrically opposite points, longitudinally projecting guide fingers, 12, which are adapted to enter the discharge passages, 4, in the valve seat, and serve as guides for the 75 valve in its opening and closing movement. Fitted in the annular recess in the body of the valve is a packing ring, 13, which, when the valve is in closed position, is adapted to engage an annular rib or projection, 14, on 80 the outer side of the valve seat and thereby prevent the entrance of liquid to the discharge passages, 4.

On the outer side of the valve, 10, are oppositely disposed, integrally formed closing 85 cams, 15, which are adapted to be engaged by opposing cams, 16, formed on and projecting radially from a sleeve or collar, 17, which is slidably mounted on the squared outer end of the stem, 7, and is held in position thereon by means of fastening nuts, 18. 90

On the inner side of the valve are formed oppositely disposed opening cams, 19, which are adapted to be engaged by co-acting cams, 20, which are formed on and project radially 95 from a sleeve or collar, 21, which is slidably mounted on the stem, 7, between the valve and the adjacent side of the valve seat.

In order to open the valve, the cams 20 are turned by means of the stem 7 to engage 100 the cams 19 on the inner side of the valve, thereby forcing said valve outwardly, but away from its seat and permitting the liquid to enter the passages 4. When the stem 7 is thus turned to engage the cams, 20, with the cams, 19, on the inner side of the valve, the cams, 16, on the sleeve, 17, on the outer end 105 of the stem, 7, will be turned out of engage-

ment with the cams on the outer side of the valve, thus permitting the valve to move outwardly. When the stem, 7, is turned in the opposite direction, the cams 20 are disengaged from the cams, 19, on the inner side of the valve, while the cams, 16, are engaged with the cams, 15, on the outer side of the valve, and the latter thereby forced into engagement with its seat, thus closing the passages, 4, in the valve seat.

In order to turn the stem 7 to open and close the valve I provide a tubular operating key, 22, said key having on its inner end a cylindrical projection, 23, having a squared bore to receive the squared head, 9, on the end of the stem 7, and with a series of radially disposed discharge passages 24, which form a communication between the interior of the body portion 1, and the passage 20 through the key, thus permitting the discharge of the liquid through the faucet and the key when the valve is in an open position.

The key, 22, is provided adjacent to the inner end of the projection 23, with an enlarged cylindrical head, 25, and on said projection, 23, adjacent to said head, is arranged a packing ring, 26, which, when the key is turned to the proper position for opening the valve, will be engaged with the seat formed by the flange 5, on the inner side of the body portion, 1, thus preventing the discharge of liquid around the outer side of the key. On the head, 25, are formed oppositely beveled lugs, 27, which are adapted to be engaged with the cam recesses, 6, on the inner side of the body portion, 1, whereby the key is held in position in said body portion and by means of which the head 25 is thrown into fluid-tight engagement with the flange, 5, when the key is turned to the position for opening the valve. The key, 22, is provided adjacent to its outer end with an operating handle, 28, and said outer end is also provided with interior and exterior screw threads, by means of which a tube or pipe may be connected with the key.

In order to prevent the passage of liquid between the valve and its operating stem, I employ a cap, 30, adapted to be screwed onto the valve, which is provided with threads to receive said cap. The cap, 30, covers the outer end of the stem and incloses the closing cams and outer side of the valve.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as defined in the appended claims.

Having thus described my invention, what

I claim as new and desire to secure by Letters-Patent, is:

1. In a beer faucet, a hollow cylindrical body portion having a closed inner end forming a valve seat, said seat having formed therein oppositely disposed discharge passages, a valve adapted to be engaged with said seat to close said passages, an operating stem revolvably mounted in said body portion, opening cams arranged on said stem and adapted to move said valve away from said seat to open said passages, closing cams on the outer end of said stem adapted to move said valve to a closed position, and a detachable tubular key to operate said stem, substantially as described.

2. In a beer faucet, a hollow cylindrical body portion having a closed inner end forming a valve seat, said seat having oppositely disposed discharge passages and a centrally disposed bearing passage, an operating stem revolvably mounted in said bearing passage, a valve slidably mounted on said stem to engage said seat, co-acting valve opening cams arranged on the inside of said valve and on said stem, co-acting closing cams arranged on the outer side of said valve and on the adjacent end of said stem, a tubular key adapted to be inserted into the outer end of said body portion and into engagement with the inner end of said stem whereby the latter is turned to operate said cams and thereby open or close said valve, and means to detachably secure said key in place, substantially as described.

3. In a beer faucet, a hollow cylindrical body portion having a closed inner end forming a valve seat, said seat having oppositely disposed discharge passages and a centrally disposed bearing passage, an operating stem revolvably mounted in said bearing passage, a valve slidably mounted on said stem to engage said seat, co-acting valve opening cams arranged on the inside of said valve and on said stem, co-acting closing cams arranged on the outer side of said valve and on the adjacent end of said stem, a tubular key adapted to be inserted into the outer end of said body portion and into engagement with the inner end of said stem whereby the latter is turned to operate said cams and thereby open or close said valve, means to form a fluid-tight engagement of said key with the body portion of the faucet when the valve is in an open position, and means to detachably secure the key in the outer end of said body portion, substantially as described.

In testimony whereof I have hereunto set my hand in presence of two subscribing witnesses.

FRIEDRICH E. BRUECKNER.
